(57) **CLAIM**

The ornamental design for the tire carrier, as shown and described.

DESCRIPTION

FIG. 1 is a perspective view of the tire carrier of the present invention, with an understanding that mirror images are possible;

FIG. 2 is a front view thereof;

FIG. 3 is a rear view thereof;

FIG. 4 is a top view thereof;

FIG. 5 is a bottom view thereof;

FIG. 6 is a front elevation view thereof;

FIG. 7 is a rear elevation view thereof; and,

FIG. 8 is a perspective view thereof in a potential environment.

The broken lines illustrate the design's environment and form no part of the claimed design.

1 Claim, 6 Drawing Sheets

FIG. 1

FIG. 3

FIG. 4
